UNITED STATES PATENT OFFICE.

HENRY M. COGAN, OF CHARLESTON, WEST VIRGINIA.

MIXING AND VAPORIZING DEVICE.

Application filed August 18, 1925. Serial No. 50917.

This invention relates to a mixing and vaporizing device for motor fuels especially adapted for use between a carburetor and intake manifold fuel supply pipes of an internal combustion engine. An object of this invention is to effect a complete mixing and vaporization of the engine fuel. Another object is to eliminate the danger of back-fire into the carburetor and yet another purpose is to reduce deterioration of lubricating oil due to non-vaporized fuel particles getting into the crank case.

The use of screens of varied shapes has been suggested for the purpose of accomplishing the afore-mentioned objects and also conical screens both singularly and in plurality have been suggested with a view to directing the fuel screens away from the walls of the pipe where the liquid particles seem prone to collect. In spite of previous attempts to use a plurality of foraminous cones the efforts to more completely keep liquid particles from the pipe walls and to more completely mix and vaporize the fuel have not been successful. Realizing the likelihood of liquid particles collecting on the walls of the fuel pipe, it has been suggested to jacket portions of this pipe with hot exhaust gases and so vaporize any particles of liquid fuel on these walls, but such a construction does not lend itself readily to standard engine construction today.

According to this invention more complete mixing and vaporization of the fuel is accomplished by a series of conical screens which not only tend to break up any liquid particles in the fuel and direct the gas stream away from the supply pipe walls but in addition these cones are connected by a screen which is preferably spaced from the pipe walls so that liquid particles contained in the fuel which might otherwise collect on the pipe walls become thinly spread over this screen and because surrounded by a moving gas stream on substantially all sides, they are broken up, vaporized, and atomized more readily than if exposed to the gas stream on only one side as would be the case were they on the pipe walls.

Fig. 1 is a side elevation of the intake manifold and carburetor of an internal combustion engine showing one form of my invention applied thereto.

Fig. 2 is a longitudinal sectional view showing the preferred form of my invention in position.

Fig. 3 is a section of another form of cone.

The preferred form of my invention is best shown in Fig. 2 and consists of a foraminous tubular member 13 having a flange 10 adaptable for securing it between a joint in the fuel intake pipe situated between the carburetor 8 and the fuel intake manifold 9.

A series of spaced finely meshed wire cones such as 7, 7', are mounted in cascade on the tubular member 13 so that their apices will point in the direction of the fuel flow in the fuel intake pipe. Each of these cones may be joined at their apices by a rod 14 which strengthens the device and adds to the surface on which the entrained fuel may spread film and evaporate.

A foraminous cylinder connecting the bases of the cones functions to mechanically support the cones and facilitates atomization and mixing by reason of the liquid particles being thinly spread out and more intimately in contact with the gas stream than if such liquid particles were collected on the pipe walls. The wire shown as connecting the apices of the cones serves to mechanically space and reinforce the cones.

In Fig. 3 is shown a modified form of my invention in which a section 16 of the cone 15 is reversed. This form has the advantage of being more compact and readily accommodates itself to a pipe which has an elbow near the joint engaging the flange of the device.

In the device of my invention the engine fuel is forced to make a series of angular turns and the entrained liquid is spread over the cones and is rapidly vaporized. The finely meshed wire catches any dust, dirt or other undesirable foreign matter and thus prevents any engine failure or deterioration due to this cause. The results of the use of my invention as shown by numerous tests are that there is less dirt, less smoking and no back firing in the motor and that the motor using my invention operates more efficiently and runs more smoothly than do those of the same type not using the device of my invention.

In using the terms "cones" and "cylinder" it should be understood that I have not intended to limit my claims to a construction in which these terms are used in a mathematical sense, since advantageous results may be obtained by the use of screens of this character which are polygonal in cross-section. The screen should, however, be substantially tapered and preferably with an included angle

of less than 90°. Furthermore the screen should have an extended surface of sufficient area to allow the passage of the requisite volume of air and gas. On the other hand 5 there should be no perforations or passages through or around the screen of sufficient area to permit the passage of flame or large particles of foreign matter.

I claim:

- 10 1. A fuel mixing device for internal combustion engines lying within the fuel intake pipe between the carburetor and the engine comprising a series of separated foraminous cone screens whose apices extend in the direction of the fuel flow and whose bases are secured to a foraminous cylinder concentric with the intake pipe and means for securing the base of said cylinder to said pipe.
- 20 2. A fuel mixing device to be placed in the fuel supply pipe between the carburetor and intake manifold of an internal combustion engine, which comprises a series of fine mesh cone screens having their large ends connected by a foraminous cylinder, means for supporting said screens in said pipe, and spacing means extending axially through said series of screens.
- 30 3. A fuel mixing device to be placed in the supply pipe between the carburetor and intake manifold of an internal combustion engine, which comprises a series of spaced screens inclined so that they tend to direct moisture away from the inner surface of the

35 supply pipe, means for supporting said screens in said pipe, and a foraminous cylinder connecting the outer extremities of said screens and of a diameter less than the inside diameter of said pipe walls.

4. A fuel mixing device to be placed in the supply pipe between the carburetor and intake manifold of an internal combustion engine, which comprises a series of longitudinally spaced conical screens having at least a portion of their sides arranged so that moisture is directed away from the inner surface 45 of the supply pipe, a foraminous cylinder connecting the outer portions of said screens and of a diameter less than the inside diameter of said pipe walls, and a flange support for said cylinder adjacent its end nearest the carburetor.

5. A fuel mixing device to be placed in the supply pipe between the carburetor and intake manifold of an internal combustion engine, which comprises a series of longitudinally spaced conical screens having at least a portion of their sides arranged so that moisture is directed away from the inner surface 55 of the supply pipe, a foraminous cylinder connecting the outer portions of said screens and of a diameter less than the inside diameter of said pipe walls, a flange support for said cylinder adjacent its ends nearest the carburetor, and reinforcing means connecting the apices 60 of said cones.
